LAUNDRY APPARATUS

Fritz Balzer, Chicago, Ill., assignor, by mesne assignments, to American Machine and Metals, Inc., New York, N. Y., a corporation of Delaware

Application November 6, 1933, Serial No. 696,831

4 Claims. (Cl. 68—18)

The invention relates to laundry apparatus and more particularly to a novel and useful system for washing, drying and handling clothes in a laundry and to various novel and useful mechanisms used in various phases of said system.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

20 Of the drawings:—

Fig. 1 is a front longitudinal elevation of a washing machine embodying certain features of the invention;

Fig. 2 is a transverse section on line 2—2 of Fig. 1;

Fig. 3 is a transverse section on line 3—3 of Fig. 1;

Fig. 4 is a vertical longitudinal section on line 4—4 of Fig. 3, broken away to show about one-half the machine;

Fig. 5 is a fragmentary section on line 5—5 of Fig. 3;

Fig. 6 is a fragmentary sectional detail on line 6—6 of Fig. 2;

Fig. 7 is a fragmentary, horizontal section on line 7—7 of Fig. 3;

Fig. 8 is a detailed elevation of one of the washing cylinder supporting arms;

Fig. 9 is an end elevation of the washing machine showing the washing cylinder in discharging position;

Fig. 10 is an elevation of a portable container or hopper for clothes;

Fig. 11 is a diagrammatic elevation of a washing and drying system embodying the invention;

Fig. 12 is an elevation, in detail, of a flexible, foraminous receptacle for clothing, shown in its discharging position;

Fig. 13 is a view similar to Fig. 12 but showing the receptacle in its closed positions; and

Fig. 14 is a detail elevation of the receptacle engaging and lifting means.

The invention is directed to providing a novel and useful laundry system and apparatus there-

for, wherein the clothes are handled in an exceedingly efficient, rapid and inexpensive manner from the washing operation on through the drying and sorting operations. An important object of the invention is to provide a laundry system which eliminates many of the unnecessary time and labor-consuming steps involved in laundry systems now in use. The invention also provides novel, simplified, relatively inexpensive and highly efficient mechanisms and devices for carrying out the various steps or phases of the laundry system.

More in detail, the invention provides, as parts of an integral and coordinated laundry-handling system, a novel washing machine which facilitates loading and unloading of the clothes and especially promotes efficient dumping of the washed clothes from the washing cylinder without a manual or mechanical lifting out of the garments from the cylinder. By virtue of the novel features of the washing machine construction, the washing cylinder may be moved easily and rapidly to a position from which the washed clothes may be discharged solely by gravity into a suitable receptacle for transfer to the dryer. The mechanical construction of the washing machine is such that the washing cylinder is movable in a straight line path from the washing position to the unloading or discharging position, and is returnable over the same straight line path.

The novel laundry system of the invention also embodies a novel form of receptacle for receiving the clothes discharged from the washing machine and for transporting them to a centrifugal dryer. Said receptacle is preferably adapted to conform to the shape of the dryer basket and novel means are provided for preforming the receptacle into said shape prior to loading it with clothes from the washing machine, and for maintaining it in said preformed shape throughout its travel from the washing machine to and into the dryer basket. The clothes receptacle is preferably formed as a flexible, foraminous bag which is adapted to conform exactly to the interior of the dryer basket when loaded with clothes. A portable container having an interior shape conforming to that of the dryer basket is provided for preforming the bag to said basket shape, for supporting it during the loading operation at the washing machine, and for transporting the loaded bag to the centrifugal dryer.

Suitable means are provided for removing the loaded, preformed receptacle from the container and introducing said loaded receptacle into the

centrifugal basket of the drying machine while maintaining the receptacle in the preformed shape imparted to it by the container. As a final phase of the system, the receptacle, loaded with the centrifugally dried clothes, is removed from the dryer and transported to a sorting table, where the receptacle is unloaded and the clothes are sorted in the usual manner.

The laundry system and apparatus hereinbefore briefly described is highly efficient and a great advance over known systems. The flexible, preformed clothes receptacle provides a very simple and inexpensive device for handling the clothes with a minimum of steps and manipulations from the washing to the sorting operation. The use of numerous expensive and cumbersome metal receptacles for holding the clothes in the dryer is eliminated as a portable container may be used for receiving and transporting additional receptacle loads of clothes during the drying operation of a previous load. Furthermore, the novel construction of the washing machine and of the clothes receptacle permits both unloading operations to be performed solely by gravity and with a minimum of labor and of mechanical parts and movements.

It will be understood that the foregoing general description and the following detailed description as well are exemplary and illustrative 30 of the invention, but are not restrictive thereof.

Referring now in detail to the present preferred embodiment of the invention, illustrated by way of example in the accompanying drawings, the various steps and instrumentalities of 35 the invention as constituting a laundry system and apparatus therefor will first be described. As shown in Fig. 11, the soiled clothes are introduced into a cylindrical washing machine 10, which, for the carrying out of many parts of 40 the laundry system may be of any one of several known types, although the washing machine hereinafter described in detail is preferable for the complete and most satisfactory working of the system as a whole.

45 After the clothes have been subjected to suitable washing treatment in the machine, they are discharged therefrom by gravity into one or more portable containers 20 for transportation to the centrifugal dryer 30. The mechanical construction of the discharging mechanism will be described in greater detail hereinafter, but may be seen generally in Figs. 9 and 11. As there shown, the washing cylinder 11 is movable from its washing position within the casing 50 10 of the washing machine to a discharging position which is on a diagonal line above and beyond the washing position. The transfer of the washing cylinder to its discharging position is preferably effected by a straight line movement of the washing cylinder, and the cylinder is returned by a reversal of that movement. When the washing cylinder is in the discharging position as shown in Fig. 9, doors 212 and 213 in the lowermost section of the cylinder are opened 55 and the washed clothes may then fall directly downwardly to a position just clear of the washing machine casing and frame.

The embodied means for receiving the clothes discharged from the washing cylinder comprises 70 a portable container 20 (Figs. 9, 10 and 11), which is a rectangular box or casing mounted on suitable casters 21. The container is provided with suitable guide means for facilitating movement of the clothes from the washing cylinder into the body of the container. As em-

bodied, two separable guide members 22 and 23 are mounted on the frame 20 and are movable together to form a flared or funnel-shaped hopper at the top of the container 20 as shown in Fig. 9. Each of said guide members comprises a rectangular outer frame with its interior surface 24 having a generally conoidal inward and downward taper. Thus when the members 22 and 23 are brought together on top of the container 20 as shown in Fig. 9, they form a funnel-shaped or bell-mouthed guide at the top of the container for receiving and guiding the clothes thereto.

Means are provided for moving the members 22 and 23 away from the top of the container 20 when the clothes are not being discharged thereinto. As embodied, each of said members 22 and 23 is pivotally mounted near its inner end on a pair of slotted arms 25, the slots of which ride over a centrally disposed pin 26 at either end of the container 20 near the top thereof. As shown in Fig. 10, the guide members 22 and 23 may be moved to a position along the side faces of the container 20 by a simple manipulation of the slotted arms 25.

In accordance with the invention, a flexible, foraminous receptacle, preferably comprising a fabric bag 40 (Fig. 13) is provided for directly receiving the washed clothes from the washing cylinder. As embodied, said bag is adapted to 30 be seated within the container 20 and said container is provided with means for preforming the bag to a shape conforming substantially to the interior surface of the centrifugal basket of the dryer 30. As embodied, the upper end or 35 mouth of the bag 40 is attached to a rigid annular frame 41 which is adapted to seat within the upper edge of the centrifugal basket (not shown). Said frame 41 is also adapted to seat within the upper edge of container 20, and a 40 suitable supporting ledge 27 is provided around the upper portion of the case 20 and preferably just below the bottom edge of the inclined hopper member 24, thereby holding the bag in position to receive the clothes as they discharge 45 into the container through the funnel-shaped mouth 24 thereof.

The container 20 is provided with means for preforming the flexible bag 40 to conform to the shape of the interior of the centrifugal basket and, as embodied, the container is provided with a central tapered core or post 28 which acts to force the bottom of the bag into a reentrant cone. Said conformation of the receptacle or bag permits the central portion thereof to fit 50 over the correspondingly formed member at the center of the centrifugal basket (not shown).

After the receptacle 40 has been seated in the container 20 and loaded with clothes as indicated in Fig. 9, the loaded container is wheeled 60 to a station adjacent a centrifugal dryer 30, as shown in Fig. 11. Means are provided for lifting the loaded receptacle 40 out of the container 20 and seating same within the centrifugal basket of the dryer 30. As embodied, a grappling device indicated generally as 50 is suspended by pulley system 51 which is adapted to travel on an overhead monorail 52. A suitable cable 53 is provided with a hook 54 for engaging the coupling link 55 of the grappling device. In its present preferred form, the grappling device comprises a plurality of hooks 56 connected to two chains 57 all suspended from the ring 55. Said hooks 56 are adapted to engage with suitable 70 75

eyes 58 which are formed at two equally spaced points on the retaining ring 41 of the bag 40. The bag 40 also comprises means for

The grappling device also comprises means for engaging the central upturned or re-entrant portion of the bag 40, thereby to maintain the pre-formed shape of the bag when it is lifted out of the container 20 and seated in the basket of the dryer 30. As embodied, the bag 40 is subdivided into a plurality of tapered quadrants or leaves 44 which, when brought together, give the bag a roughly conical or tapered shape as shown in Fig. 13. Suitable closure means for bringing together the four quadrants or leaves of the bag may comprise the hookless fasteners or "zipper" devices 45, as shown, although other suitable means may be used in lieu thereof. The shape of the several quadrants 44 is such that a complete closure is not made at the bottom of the bag, but a small annular opening 46 remains when the 20 quadrants are drawn together. A plurality of coupling rings 47 are fixed to the lower ends of the several quadrants and, when the lower portion of the bag is pushed up to form the re-entrant conical shape as hereinbefore described, 25 said rings protrude upwardly through the opening 46 as shown in dotted lines of Fig. 13.

30 The embodied means for engaging said rings 46 to retain the bag in the preformed shape comprises a centrally suspended grappling cone 59 which hangs from the ring 55 of the grappling device by a chain 60. The cone 59 is provided with a cylindrical mouth 61 which is adapted to fit over the annular end opening 46 of the bag bottom. Hooks 62 are mounted around the bottom 61 of the cone and are adapted to engage the similarly spaced rings 47 on the bag bottom. It will be clear, therefore, that when the grappling hooks 56 and 62 of the grappling device 50 are connected to the eyes 58 and rings 47, respectively, of the bag, the bag may be lifted out 40 of the container 20 while preserving the conformation imparted thereto by the container. This operation is indicated on the left of Fig. 11, after the loaded bag or

As shown in Fig. 11, after the loaded bag or receptacle is lifted from the container by the grappling device 50 it is moved along the monorail to a position directly over the open centrifugal dryer 30. It is then lowered into the centrifugal basket, where it seats immediately by virtue of its preformed shape. The seating ring 41 engages a suitable retaining ledge (not shown) near the rim of the basket. The grappling device is then disconnected and the drying operation is carried out in the usual manner, the foraminous bag permitting centrifugal extraction of the water from the clothes.

from the clothes.

After the drying operation is completed, the lid of the dryer casing is raised and the grappling device again connected with the bag or receptacle 40. The receptacle is then raised from the basket and transported along the mono-rail to above the sorting table 65. The central grappling cone 59 is then disengaged from the rings 41 and the loaded bag will collapse into the form shown in full lines in Fig. 13. The zippers 45 will then be pulled open permitting the dry clothes to fall onto the sorting table. The bag may then be reclosed, the eyes 58 disengaged from the grappling hooks 56, and the bag is ready for placing again in a container 20 for reloading, while the grappling device may be returned to the dryer or to a container to take up its operations in the cycle. It will be understood, of course, that several dryers and several grappling devices may be provided and used simultaneously, and that

the different grappling devices may be used to carry out the different operations of transporting the receptacle from the container to the dryer and of transporting the dried receptacle from the dryer to the sorting table.

Referring now to the construction of the present preferred embodiment of the washing machine per se, the perforate washing cylinder or drum 11 (Fig. 2) is mounted within a cylindrical casing 10, the casing being supported on a plurality of supporting castings 10. At either end of the cylindrical casing 10 there is provided a superstructure 12 for housing the overhead driving elements, and a lower extension 12' for housing part of the driving mechanism which projects below and beyond the drum casing proper. Said end casings 12 and 12' are preferably integral parts of the casing support castings 10 at each end of the machine.

The invention provides separate actuating and controlling means for imparting rotary movement to the washing drum 11; for actuating the casing closure to permit access to the drum and to re-enclose it; and for effecting the discharging and return movements of the drum from and to the casing. These three sets of actuating and controlling means will now be described in the order set forth.

order set forth.

Referring first to the means for imparting the rotary washing movement to the washing drum 30 or cylinder 11, said drum is provided at either end with a stud shaft 15 suitably fixed to the end plate 74 of the drum. The shaft is rotatably journaled in a block 17, which is slidably supported in the diagonally disposed frame castings 35 78 and 79. The block 17 is a relatively long and narrow casting (Fig. 8) having a centrally disposed opening 80 for rotatably supporting the shaft 15 and is provided with relatively thin side flanges or tongues 81 which fit slidably within conforming grooves 82 in the upper face of casting 78 and the lower face of casting 79 respectively. Said frame castings 78 and 79 are bolted to the side walls 83 of the end casing support 70 and thereby afford fixed supports for the drum 11 in its rotary and translation movements.

Referring now to the means for imparting rotation to

The embodied means for imparting rotation to the shafts 75 comprises a relatively large gear wheel 85 the hub 86 of which is keyed to the outer end of the shaft 75, a suitable guard plate 87 being fixed to the end of the shaft and overlying the end of the hub. Rotary motion is imparted to the gear wheel 85 from a drive motor 90 as follows:

as follows: The motor 90 is mounted above and to the rear of the washing drum and preferably between the ends thereof, being supported by a suitable bracket casting 91 which is attached to the rear portion of the main casing support 70. The motor shaft 92 is provided with a sprocket or pulley 93 which engages a chain or belt 94, the other end of the belt engaging the driving surface of a relatively large drive pulley 95. The drive pulley 95 is drivingly connected to a main drive-shaft 98 which extends the length of the machine, being journaled at either end 99 in the outer frame of the casing 12. A suitable intermediate supporting bracket 100 is provided centrally of the machine for supporting the rotating shaft 98, said bracket being fixed to the motor bracket 91. The shaft 98 is imparted to 70

Driving force from the shaft 98 is imparted to gear wheels 85 through pinions 105 at either end of the shaft which intermesh with idler spur gears 106. The spur gears 106 are fixed to either end of the upper drive-shaft 107. Said shaft extends 75

the length of the machine above and parallel to shaft 98 and is rotatably seated near either end in arcuate slots 108 formed in the inner faces of the end casings 12. The shaft is pivotally supported at its ends and intermediately thereof by links 109, the lower ends of which are journaled on the shaft 98 and the upper ends on shaft 107. The complete driving connections from the motor 90 to one of the gear wheels 85 are shown in Fig. 3, 10 which also discloses the structure of the upper end casings 12 which house the driving gears.

Referring now to the embodied means for actuating and controlling the closure for the casing to permit access to the washing drum and movement 15 of the drum to and from the casing, a substantially semi-cylindrical telescoping closure is provided on the main cylindrical casing 10. As shown (Fig. 2), the cylindrical casing comprises a hemicylinder 10 which is a fixed part of the casing, the 20 other half of the cylindrical casing comprising two slidable segments 120 and 121. The segment 120 is of slightly greater diameter than that of the fixed hemicylinder 10 and is adapted to slide thereover in the arcuate guideways 122 at either 25 end of the cylindrical casing 10. The door segment 121 is of slightly greater diameter than the intermediate segment 120 and is slidably rotatable in the outer arcuate guideways 123 which circumscribe the inner guideways 122.

30 In Fig. 2, the closure segments 120 and 121 are shown in their closed positions, the two segments being extended to complete the cylindrical closure about the drum 11. In that position, the lower edge of door segment 121 is seated in a cushioned, water-tight groove 125, suitably fixed to the terminal edge of hemicylinder 10, thereby serving as a stop for the door closure. The abutting edges of segments 121 and 120 are operatively connected by the interlocking flanges 128 and 35 129 whereby the lower segment will draw after it the upper segment to complete the closing action.

In the opening movement of the door segment, it will be clear that the outer segment 121 is 40 adapted to slide over the outer surface of segment 120 during the first half of the opening movement. When the outer door 121 has been moved to entirely overlie segment 120, the flange 129 will engage the upturned flange 130 on the rear edge of 45 segment 120 and thereafter the two segments will travel together in their respective guide grooves to the limit of their opening movement. The edge 131 of the leg casting 70 provides a suitable stop for the leading edge 130 of the inner segment 120 at the completion of the opening movement.

The embodied means for effecting the opening and closing movements of the door segments comprises, primarily, the lifting handles 134 on the outer periphery of the door segment 121. By these handles, the door 121 may be raised manually until it completely overlaps segment 120, thereby exposing the drum 11 for inspection and the loading of clothes. For completion of the opening 50 action, which is usually effected to permit egress of the drum to the discharging position, a mechanical drive is imparted to the door segment 121 so as to move it and segment 120 together to the full open position. The embodied means for 55 effecting said mechanical drive comprises arcuate racks 136 on the periphery of segment 121 at either end thereof. Suitable driving means for engaging said racks and imparting rotary movement thereto comprises pinions 138 at either end 60 of shaft 140, said shaft being driven from a cen-

trally disposed sprocket wheel 141 through a chain drive 142 from a motor 143. The motor is mounted on the motor bracket 91 substantially centrally of the machine and is provided with a suitable gear reducer 144 for transmitting the drive to the 5 chain 142.

It will be noted that the pinions 138 are adapted to engage the racks 136 when the door segment 121 has been moved by hand to entirely overlie segment 120. Thereupon the pinions engage the 10 racks and move both segments together as desired. The return movement of the segments may be effected by reversing the motor 143, thereby bringing the door segment 121 to a position whence it may be completely closed by manual 15 actuation.

It will be noted that the door segment 121 is provided with the usual sub-doors 146 for permitting inspection during the washing operation, introduction of soap, and the like.

Referring now to the present preferred means for moving the washing drum or cylinder 11 from the washing position to the discharge position and vice versa (Fig. 9), the invention embodies devices for effecting said movements as a 25 straight line lift and return of the entire drum. As hereinbefore described, the drum shafts 75 are rotatably supported in slidable blocks 77, the edges 81 of which are adapted to slide in the groove 82 of the inclined frame members 78 and 79. Thus by imparting suitable translational movement to the blocks 77, the entire cylinder assembly may be caused to travel upwardly and outwardly along the guideways 78 and 79 from the position shown in Fig. 2 to the position in 35 Fig. 9.

For effecting said translational movement, either end of the shaft 75 is engaged, through the hub 86 of gear wheel 85, by journals formed at the ends of link arms 150. The other end 151 of said link arm is drivingly connected to a rotating crank 152 by a suitable stud bolt 153. Rotary motion is imparted to the crank 152 in the direction indicated by the arrows in Figs. 3 and 9 to effect the desired translatory reciprocating movement 40 for the end of the link arm 150. The driving means for effecting said rotary motion comprises a motor 155 seated on the motor bracket 91 and driving vertical shaft 156 through a suitable worm gear reduction 157. The shaft 156 is provided at 45 its lower end with a beveled pinion 158 which meshes with a beveled pinion 159, keyed to a horizontal shaft 160. Said shaft 160 is suitably journaled in the casing casting and has spur gears 165 keyed to its outer ends. Said spur gears mesh with the periphery of gear wheels 166 mounted on stud shafts 167, which are threaded into suitable bosses in the casing casting 12'. The driven end of crank 152 is drivingly connected to the gear wheel 166 by bolts 168. It will be noted that slide 77 is provided with a yoke 169 at its lower end to straddle the shaft 167.

In the operation of the mechanism for moving washing drum 11 to the discharging position shown in Fig. 9, the rotary drive of the drum is 60 first stopped and then the cover segments 120 and 121 are moved to the full open position as hereinbefore described. The drive motor 155 is then started and the actuation of link 151 will slide the block 77 and the shaft 75 upwardly 65 and outwardly to the full extension of the crank 152 and link 151. In that position the drum 11 will be substantially fully ejected from the interior of the cylindrical casing 10, as shown in Fig. 9. The motor 155 will then be stopped and 70 75

the drum may be maintained in the extended discharging position so long as desired. When it is desired to retract the drum to washing position, the motor 155 is again started and the continuing movement of crank 152 will retract the link 151 and the drum therewith to the initial position.

Means are provided for effecting rotary movement of the drum in its extended or discharging position so as to bring the discharge doors 12 to the desired angular position at the bottom of the drum. As embodied, the gears 106 and their driving connections are adapted to remain in mesh with the drum gear wheels 85 continuously. As shown, arms 185 are pivotally mounted at one end upon stub shafts 15 and at the other upon shaft 107 adjacent the gear wheels 85 and gears 106 respectively so that, in conjunction with links 109, the correct mesh between the said gears is maintained in fixed relation regardless of the rectilinear movement of gear wheel 85 and drum 11. The gear 106 is mounted for a limited rocking movement, together with shaft 107, about shaft 98 as an axis, thereby to allow the drive gear 106 to accommodate itself to the rectilinear motion of the drum and gear wheel 85 without disengaging the meshing of the gear teeth. Accordingly, as hereinbefore described, the pivotal arms 109 permit swinging movement of the shaft 107 about the lower shaft 98, the arcuate slots 108 permitting said rocking movement of the shaft within the end casings 12. It will likewise be clear that the casings 12 are shaped to accommodate the limited angular movement of the gears 106 during this displacing action of the drum. Suitable guards 180 are mounted about the outer portion of the gear wheels 85 and are adapted to move outwardly with the drum.

It will be clear, therefore, that when the drum is moved outwardly from its driving position to its discharging position, arms 185 force the gears 106 and shaft 107 upwardly and backwardly as the drum moves outwardly and that as said outward movement is continued, the gear 106 lowers again after the point of maximum displacement has been passed. Thus, when the drum is in the discharging position shown in Fig. 9, it may be rotated to any desired angular position by inching the motor 90, which remains in driving engagement with the gear wheel 85 at all times.

Referring now in greater detail to the clothes-discharging means on the washing drum 11, the doors 212 and 213 are formed as pivotally mounted segments of the perforated periphery of the drum 11. The doors are mounted on suitable hinges 170 (Figs. 2 and 9). Suitable latching means 171 are provided for locking the doors in closed position against the end walls 14 of the drum. In a preferred form, the drum is subdivided longitudinally into two or more compartments by intermediate partition walls 172 and with such construction suitable spring latches 173 may be provided for fixing the inner edges of the doors to the partition.

The interior of the drum may be provided with the usual projecting members 175 and 176 for effecting a tumbling action on the clothes during the washing operation. For facilitating the discharge of clothes through the doors 212 and 213, the relatively large projecting members 177 and 178 are formed at either side of the doors and provided with relatively long inclined surfaces which tend to cause the clothes to slide downwardly and inwardly towards the door opening.

The invention in its broader aspects is not limited to the specific mechanisms shown and described but departures may be made therefrom within the scope of the accompanying claims without departing from the principles of the invention and without sacrificing its chief advantages.

What I claim is:

1. A washing machine including in combination a stationary casing, a washing cylinder rotatably mounted within the casing, means for moving the cylinder upwardly and laterally to an unloading position outside the casing, and guiding means for causing the cylinder to travel in a straight line throughout its movement between said positions, said cylinder moving means comprising a power driven crank having a connecting rod pivotally attached to it and the cylinder whereby the crank will rotate unidirectionally to raise and lower the cylinder in said straight line, and driving means for rotating the cylinder in any position of its travel comprising a gear about the cylinder and a driving gear meshing therewith and connected to a power source, said driving gear being movable toward and away from the path of movement of the cylinder while remaining in engagement with said power source, whereby the driving gear may remain in mesh with the cylinder gear throughout its movement.

2. A washing machine including in combination a stationary casing, a washing cylinder rotatably mounted within the casing, means for guiding and moving the cylinder upwardly and laterally to an unloading position outside the casing including an arm connected to the cylinder, a rotary crank member for moving the arm, a gear on the cylinder shaft and a driving gear therefor constantly in mesh therewith, said driving gear being mounted on an axis movable toward and away from the path of movement of the cylinder.

3. A washing machine including in combination a stationary casing, a washing cylinder rotatably mounted within the casing, means for guiding and moving the cylinder upwardly and laterally to an unloading position outside the casing including a cylinder supporting and guiding member, a link connected with the cylinder for moving the cylinder under the control of said guiding member and a power driven rotary crank connected to the link, whereby unidirectional rotation of the crank will raise and lower the cylinder along the path imposed by the guiding member and a gear on the cylinder shaft, a driving gear therefor constantly in mesh therewith, said driving gear being mounted on a movable arm to permit arcuate travel of the driving gear toward and away from the path of movement of the cylinder.

4. A washing machine including in combination a stationary casing, a washing cylinder rotatably mounted within the casing, driving means for rotating the cylinder for washing operation, means for moving the cylinder upwardly and laterally to an unloading position outside the casing, and guiding means for causing the cylinder to travel in a straight line throughout its movement between said positions, and means for driving the cylinder in the unloading position comprising a gear on the cylinder shaft and a driving gear meshing therewith and having bodily movement toward and away from the path of travel of the cylinder.

FRITZ BALZER.
